UNITED STATES PATENT OFFICE

LORA E. POOLE, OF ANDERSON, INDIANA, ASSIGNOR TO DELCO-BEMY CORPORATION, OF ANDERSON, INDIANA, A CORPORATION OF DELAWARE

METAL WORKING MACHINE

Application filed July 22, 1929. Serial No. 380,168.

This invention relates to a machine used in the manufacture of field poles and in particular to a machine for drilling, tapping, and countersinking holes in field poles.

An object of this invention is to reduce the cost of producing field poles for dynamo electric machines by reducing the time, the amount of labor required to drill, tap, and countersink the holes. This has been accomplished by providing a dial having a plurality of work holders arranged in groups, which is intermittently rotated so as to position the work pieces held by each group in a series of operating stations, where the holes are drilled, or countersunk or tapped.

Another object of this invention is to provide indexing means for the rotary turn table, or dial which requires a very short time for the indexing and which provides a sufficiently long rest period of the dial to permit the respective tools to perform their operation.

Another object of this invention is to secure a uniform product. This has been accomplished by providing supports for the work pieces so that each work piece is held in a predetermined position when it is gripped by the clamps, provided therefor, on the dial. This insures the positioning of the holes a uniform distance from one of the ends of the work pieces.

Another object of this invention is to properly position the work piece peripherally on the dial. This has been accomplished by providing a set of clamps which align the work pieces.

Another object of this invention is to eliminate the labor required to remove the work pieces after all of the operations have been performed. This has been accomplished by providing means for automatically ejecting the work pieces from the clamps after the operations have been performed.

Further objects and advantages of the present invention will be apparent from the following description, reference being had to the accompanying drawings, wherein a preferred embodiment of one form of the present invention is clearly shown.

In the drawings:

Fig. 1 is a plan view of the machine.

Fig. 2 is a sectional view taken on the line 2—2 of Fig. 1. For convenience Fig. 2 has been drawn as though the section line 2—2 were a straight line. 55

Fig. 3 is a sectional view taken on the line 3—3 of Fig. 2.

Fig. 4 is a sectional view taken on the line 4—4 of Fig. 2 and of Fig. 3.

Fig. 5 is a sectional view taken substantially on the line 5—5 of Fig. 2. 60

Figs. 6 and 7 are fragmentary detail views showing the clamps in the open position and in the closed position, respectively.

Figs. 8 and 9 are fragmentary detail views 65 showing a side elevation of the clamps as disclosed in the Figs. 6 and 7. Fig. 9 discloses one of the clamps in section taken on the line 9—9 of Fig. 7.

Fig. 10 is a sectional view taken on the line 70 10—10 of Fig. 11.

Fig. 11 is a fragmentary sectional view taken on the line 11—11 of Figs. 1 and 10.

Fig. 12 is a sectional view taken on the line 75 12—12 of Figs. 2 and 13.

Fig. 13 is a sectional view taken on the line 13—13 of Figs. 1 and 12.

Fig. 14 is a detail view of the reversing clutch disclosed in Fig. 13.

Fig. 15 is a sectional view taken on the line 80 15—15 of Fig. 14.

Fig. 16 is a fragmentary sectional view taken on the line 16—16 of Fig. 11.

Fig. 17 is a fragmentary sectional view 85 taken on the line 17—17 of Fig. 2.

Figs. 1, 2, 3, 4 and 5 have been drawn to a smaller scale than the other figures.

Figs. 14—17 inclusive have been drawn to a larger scale than the other figures.

In the manufacture of dynamo-electric machines, especially, of the smaller types, each of the field poles are attached to the frame by means of a single screw extending from the frame threadedly engaging an aperture provided therefor in the core of the pole. 90

At least three operations are required to provide this, namely, (1) drilling the hole, (2) countersinking the hole and (3) tapping the hole. The drilling may be done in one or in several steps. The steps of counter- 95

sinking and tapping may be reversed from the order given above.

In the drawings the reference character 20 discloses the field poles held in position by a pair of clamps 22 and 24 which are provided with fingers 26 and 28 which engage the edges of the core of the field pole 20 as clearly seen in Fig. 7. These clamps 22 and 24 are pivotally mounted on the pins 30 and 32 extending through the support 34 which is attached to the dial 54 and which is provided with a pair of recesses for receiving the clamps 22 and 24. The support 34 is provided with the seats 36 and 38 which support the tips of the pole shoes 20. The clamps 22 and 24 have the fingers 26 and 28 moved into engagement by means of an oval cam 40 engaging the lobes 42 and 44 of the clamps 22 and 24, respectively. Cam 40 is attached to a pin 43 provided with a head 45, carrying a handle 46 which rotates the cam either manually or automatically.

When the handle 46 is moved from the position disclosed in Fig. 7, to the position disclosed in Fig. 6, by a mechanism which will be described later, the spring 48 engaging the recesses 50 and 52 actuates the lobes 42 and 44 toward each other thereby spreading the fingers 26 and 28.

The driving mechanism for the rotary turn table 54 as best seen in Figs. 2-4 includes a speed reducing unit 60 driven by an electric motor not shown. The speed reducing unit 60 comprises a driven shaft 62 journalled in the bearings 64 and 66 and carrying a gear 68 meshing with a gear 70 freely rotatable on the shaft 72, journalled in the bearings 74 and 76. Integral with the gear 70 is a driving clutch member cooperating with a driven clutch member 77 splined on the shaft 72. A clutch controlling handle 78 pivoted on the pin 80 terminates in a bifurcated end 82 carrying the pins 84 and 86 which cooperate with an annular recess 88 in the movable clutch member 77 as best seen in Fig. 4. A worm 90 keyed to the shaft 72 meshes with the worm gear 92 keyed to the shaft 94, connected to a shaft 96 by a coupling 98. The shaft 96 is journalled in the end thrust bearing 99, seated in the bracket 100 carried by the frame 102 and carries an elliptical gear 104 which meshes with an elliptical gear 106, keyed to the shaft 108, journalled in the bearings 110 and 112, seated in bracket 100. The plate 114 keyed to the shaft 108 carries the Geneva gear driving member 116 which cooperates with the Geneva gear driven member 118, carried to the shaft 56, to drive the rotary dial 54 through member 122 keyed to the shaft 56 and adjustably connected to the rotary dial 54. Member 122 as best seen in Fig. 1, has a pair of arms 124 and 126, positioned between the brackets 128 and 130 and the brackets 132 and 134, respectively. Each of these brackets carries a set screw 136 which is used

in adjusting the relative position of dial 54 with respect to the shaft 56 and the Geneva gear driven member 118. As best seen in Figs. 3 and 4 the part 140 which is secured by screws 142 to the plate 114 is a usual Geneva gear locking member which cooperates with a cylindrical recess 144 of the Geneva gear driven member 118. By providing elliptical gears for driving the driving member 116 of the Geneva gear, member 116 is rotated very rapidly while engaging the driven member 118 so that a short time interval is required in indexing the work support dial 54, leaving more time for the tools to operate on the work piece which will be described later.

Brackets 150, 152, 154, 156 and 158 which are each attached to the frame 102 by suitable screws not shown slidably support the tool carriers 160, 162, 164, 166 and 168 respectively. The carriages 160, 162, 164, and 166 are identical in construction, one of which is shown in section in Figs. 10, 11 and 16, which will now be described.

The stub shaft 170, connected to the motor 172 through the flexible coupling 174, has fixedly attached thereto a gear 176 which is provided with journals 178 and 180, journalled in the bearings 182 and 184 mounted in the frame 186. The gear 176 meshes with a gear 188 which is provided with journals 190 and 192 journalled in the bearings 194 and 196 supported in the frame 186 and which is keyed to a spindle 198. The nut 200 threadedly engaging the spindle 198, cooperates with a shoulder 202 integral with the spindle 198 to prevent endwise movement of the spindle 198 with respect to the non-rotatable quill 204. The end thrust bearings 206 and 208 permits the spindle 198 to be freely rotated even though there is an end thrust upon the spindle 198 from the tool which will appear more fully later. The gear 176 also meshes with a gear 210, journalled in the bearings 212 and 214 and keyed to the spindle 216 which is journalled in the end thrust bearings 218 and 220 located at each end of the non-rotatable quill 222. The spindles 198 and 216 carry each a chuck 224 only one of which is shown. The details of the chuck 224 have not been shown for the reason that these do not form a part of this invention and for the reason that their construction is well known to a person skilled in the art.

The tool 228 which is shown as a drill is held and rotated by the chuck 224 and journalled in the bearings 232 carried by a buffer 236, attached to a quill 238, by the screws 240 and 242. A nut 244 threadedly engaging a reduced end of a suitable stub shaft 246 holds the quill 238 in position. The shaft 246 is non-rotatably mounted in a recess provided therefor in the frame 186 by a screw 247 engaging a set screw seat 249. Rotation of a quill 238 is prevented by a key 248 passing through the shaft 246 and extending into the

longitudinal slots 250 and 252 diametrically arranged in the quill 238. Whenever the buffer 236 strikes an object such as a work piece it is permitted to move inwardly on the shaft 246 against the force of the helical spring 254 abutting quill 238 and the collar 256 integral with the stub shaft 246. The bearings for the drills and the buffer may be omitted from all the carriages excepting carriage 160 as the hole in the pole shoe started by the drills in the first carriage will align the succeeding tools and guide them.

Whenever it is found necessary to substitute a new tool for the tool 228, it is necessary to adjust the position of the quills 204 and 222 and the spindles 198 and 216 with respect to each other due to the unevenness of the length of various tools caused by sharpening etc. In order to accomplish this, a gear 260 located in the aperture 262 in the frame 186 meshes with the teeth 264 on the quill 204, and a gear 266 located in the opposite end of the aperture 262 and engaging teeth provided therefor, not shown, on the quill 222 are used to adjust the quills 204 and 222 outwardly or inwardly with respect to the frame 186 and with respect to each other upon the loosening of the nut 268, threadedly engaging an end of the bolt 270 passing through the gears 260 and 266. After the quills 204 and 222 have been adjusted the nut 268 is tightened so as to prevent movement of the gears 260 and 266 thereby holding the quills in adjusted position.

As the carriages 160, 162, 164 and 166 are reciprocated on the brackets 150, 152, 154 and 156, respectively, by a driving mechanism which will be described later, the tools carried by each of the carriages are brought into working relation with the field poles 20, carried by the dial 54, so as to drill a hole in each of the field poles and countersink this hole. Preferably the tools in the tool carriages 160, 162 and 164 are drills for making the holes and the tools carried by the tool carriage 166 are tools for countersinking the holes previously drilled. That is, the drills carried by carriage 160 drills in each pair of field poles, holes about one-third ways through the field pole located at station A in Fig. 1. After this has been done the dial 54 is indexed to position B, where the drills carried by the tool carriage 162 drills the second one-third distance through the field poles. After these field poles have been positioned at station C by indexing of the dial 54, the remainder of each of the holes is drilled by the drills carried by the tool carriage 164. When the field poles are moved to position D by indexing the dial 54, the holes are countersunk by the countersinking tools carried by the tool carriage 166. When the pole shoes located at D are moved to station E, the holes are tapped or threaded by the taps carried

by the tool carriage 168, the details of which will now be described.

The tool carriage 168, as best seen in Figs. 12, 13, 14 and 15 inclusive, includes a stub shaft 280, connected to the motor 173 through a flexible coupling 284. The stub shaft 280 has fixedly attached thereto a gear 286 provided with the journals 288 and 290, journalled in the bearings 292 and 294, mounted in the frame 296. The gear 286 meshes with a gear 298, which is keyed to a tubular sleeve 300, journalled in the bearings 302 and 304. A pinion 306 which is keyed to the tubular sleeve 300, meshes with a pinion 308, resting on the end thrust bearing 310, journalled on the stub shaft 312. The pinion 308 meshes with the pinion 314, keyed to a tubular sleeve 316, coaxial with the tubular sleeve 300. Through this driving mechanism the tubular sleeve 300 is rotated in the opposite direction from tubular sleeve 316. A spindle 318 is journalled in the bearings 320, 322 which are press fitted into the tubular sleeves 300 and 316 respectively and in bearing 323 carried by the frame 296. A pair of projections 324 and 326 form teeth which cooperate with shoulders 328 and 330 on the tubular sleeves 300 and 316, respectively to rotate the spindle in one direction or the other depending upon which sleeve the teeth engage. The projections 324 and 326 extend along the shaft a distance equal to slightly less than the minimum distance between the ends of the tubular sleeves 300 and 316. The projections 324 and 326 are provided with the parallel faces 332 and 334, which lie in planes normal to the axis of the spindle 318. The faces 332 and 334, lie on each side of the plane, determined by the bisector of the two projections and the axis of the spindle. The projections also terminate in the beveled surfaces 336 and 338, the surface 336 cooperating with the inclined surface 340 of the sleeve 300 to drivingly disconnect the spindle 318 from the tubular sleeve 300 upon the happening of certain events which will appear more fully later, and the beveled surface 338 cooperating with the inclined surface 342 to drivingly disconnect the spindle 318 from the sleeve 316 upon the happening of certain other events.

After the tool carriage 168 is moved towards the left as viewed in Fig. 13, the spindle 318 will be stopped in its movement towards the left when the tool carried thereby, engages the work. This will cause either a shoulder of the projection 324, or a shoulder of the projection 326 to engage the shoulder 328, carried by the tubular sleeve 300 so as to rotate the spindle 318 in the same direction as the direction of rotation of the tubular sleeve 300. When the flat surface 332 engages the flat surface 346 on the tubular sleeve 300 the tool carried by the spindle 318 will be actuated into the work piece so as to cut threads in the hole in the field pole. Immediately

upon reversal of the tool carriage 168 so that it is advanced towards the right as viewed in Fig. 13, the tap which is carried by the tool spindle 318 will prevent the spindle 318 to advance towards the right with the tool carriage 168, thereby releasing the driving engagement between the tubular sleeve 300 and the spindle 318. The shoulder 330 on the tubular sleeve 316 will come in contact and drivingly engage either the shoulder 331 on the projection 324 or the shoulder on the projection 326, so as to cause the spindle 318 to rotate in the opposite direction, thereby retracting the tap from the hole in the field pole.

The gear 286, also meshes with a gear 350, journalled in the bearings 352 and 354, and keyed to the tubular sleeve 356. The pinion 358, keyed to the sleeve 356 meshes with a gear 360 which rests on an end thrust bearing and is journalled on a stub shaft not shown, and which meshes with a gear 362, keyed to the tubular sleeve 364, thereby driving the sleeve 364 in a direction opposite to the direction of rotation of the tubular sleeve 356.

The spindle 366 which is identical in construction to the spindle 318 is journalled in the bearings 368 and 370, press fitted in the tubular sleeves 356 and 364 and in the bearing 371 carried by the frame 296. This spindle is provided with a pair of projections forming the teeth 324 and 326 which are identical to the teeth described in connection with the spindle 318. From the description of the reversing of the spindle 318 it can readily be seen that the direction of rotation of the spindle 366 is reversed upon the reversal of the tool carriage 168.

The driving mechanism for reciprocating the carriages 160, 162, 164, 166 and 168 includes a pair of integral cams 370 and 372, attached to a wheel 374, carrying a gear 376 which meshes with a gear 378, keyed to the rotating shaft 96. The wheel 374 rests on the end thrust bearing 380 and is journalled on the bearing 382, integral with the support 384, carried by a substantially annular member 386, supported on the frame 102. The pitmen 390, 392, 394 and 396 are adjustably attached to the lugs 400, 402, 404 and 406 which are attached to the carriages 160, 162, 164 and 166 respectively. The pitmen 390, 392, 394 and 396 are also attached to the sliding guides 410, 412, 414 and 416 respectively which are guided radially in the radial slots 430, 432, 434 and 436 in member 384 and which carry the cam followers 420, 422, 424 and 426, respectively. From this construction it can be readily seen, that as the cam 370 is rotated the cam followers 420, 422, 424 and 426, will cause the tool carriages to be reciprocated towards and away from the work. By adjusting the nuts that attach the pitmen 390 to the lugs, the relative distance from the

dial 54 to the tools carried by the tool carriages may be adjusted.

The pitman 398 is adjustably connected to the lug 408 carried by the carriage 168 and the other end threadedly engaging the sliding guide 418, guided in the radial slot 438 in member 384. The guide 418 carries a cam follower 428, which cooperates with the cam 372 to actuate the carriage 168 towards and away from the pole pieces, carried by the dial 54. It can be readily seen from the contour of the two cams 270 and 272 that the carriage 168 will be reciprocated much further than the other carriages. The reason for this unequal length of reciprocation is that the tool carried by the carriages 160, 162 and 164, penetrate the work only one-third the distance of the thickness of the work piece and the tools carried by the carriage 166 only countersink the holes while the taps carried by tool carriage 168, necessarily have to travel through the entire holes before completing their operation.

Operation

The operator places the field pole between the fingers 26 and 28 with the tip of the pole shoe resting on the shoulders 36 and 38 and the lower edge of the field pole resting upon the support 450 or 452 carried by the brackets 454 and 456, respectively, each of which are attached to the support 384 at station F as best seen in Figs. 1, 7 and 9. By placing the lower end of the field pole on the support 450 and 452, as the case may be, the hole to be drilled, countersunk, and tapped will always be the same distance from one end of every field pole operated upon. After the field pole has been so positioned the operator rotates the handles 46 in a clockwise direction as viewed in Fig. 1, so as to cause the fingers 26 and 28 to engage the shoulders 27 and 29 of the core of the field pole, thereby adjusting the field pole peripherally so that the center of the hole to be drilled will bisect the distance between the shoulders 27 and 29 and the distance between the tips 36 and 38. After the field poles thus inserted are positioned at station A indexing the dial 54 twice, the drills carried by the tool carriage 160, will drill one-third distance through the pole piece during a rest period of the dial 54. After the tool carriage has been retracted the cam followers travel in the circular portion 460 of the cam 270, or in the circular portion 462 of the cam 372, as the case may be, during the indexing of the dial 54. When the field poles are at position B the second one-third of the hole is drilled by the tool carried by the tool carriage 162, etc., until all of the operations have been performed at stations A, B, C, D and E. When the field poles pass from station E to station F, the handles 46 come in contact with a trip or release 470, attached to the support 184 which permits the springs 48 to move

the lobes 42 and 44 towards each other thereby spreading the fingers 26 and 28, thus releasing the pole shoes which are discharged through the chute 472 into a suitable receptacle not shown. Whenever it is desired to stop the machine, the operator actuates handle 78 which disengages the clutch.

It can be readily seen that this machine will perform all the aforementioned operations on the field poles automatically, after they have been inserted by the operator at station F. By performing all of these operations in one machine which is handled by one operator, the cost of producing field poles is greatly reduced and a more uniform product is secured.

While the form of embodiment of the present invention as herein disclosed, constitutes a preferred form, it is to be understood that other forms might be adopted, all coming within the scope of the claims which follow.

What is claimed is as follows:

1. A machine for operating upon field pole pieces, comprising in combination, tools for operating upon the pole pieces, a rotary dial for presenting the pole pieces to the operating tools, said rotary dial including seats for supporting the tips of the pole shoes, a pair of fingers for gripping and aligning each pole piece in said seat, cam means for causing the fingers to grip and align the core of the pole piece, said fingers being carried by the rotary dial.

2. A machine for operating upon field poles comprising, in combination, a tool for operating upon said field pole; a rotary dial for presenting the field pole to the operating tool, clamping means for clamping the field pole to the dial, said clamping means including a pair of clamps each clamp comprising a finger and a lobe; cam means engaging each lobe thereby causing the fingers to grip the core of the field pole; a Geneva gear driving mechanism for indexing the dial so as to present the field pole to the operating tool; and elliptical gears for driving the Geneva gear driving mechanism, said elliptical gears being so arranged as to require a short integral of time to index the rotary dial so as to leave more time for the tool to operate upon the field pole during the rest period of the dial.

3. A machine for drilling, countersinking, and tapping holes in field pole pieces comprising, in combination, a drill; a carriage for said drill; a countersinking tool; a carriage for said countersinking tool; a tap; a carriage for said tap; a rotary dial for presenting the pole pieces to each of said tools; clamps on said rotary dial for clamping the pole pieces in position; a Geneva gear driving mechanism for indexing the dial so as to position a pole piece in alignment with each of said tools; and cam means for recipro-

cating the tool carriages towards and from the pole piece during a rest period of the dial so as to permit the drill to operate on one pole piece, so as to countersink the hole in the preceding pole piece and so as to tap the hole in the preceding pole piece, said cam means including a plurality of concentric cams in a plane parallel to the plane of the dial.

In testimony whereof I hereto affix my signature.

LORA E. POOLE.
